(57) **CLAIM**

The ornamental design for a heart shaped pedal, as shown and described.

DESCRIPTION

FIG. 1 is a front perspective view of a first embodiment of my new, original and ornamental design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is a front perspective view of a second embodiment of my new, original and ornamental design;

FIG. 9 is a front view thereof;

FIG. 10 is a right side view thereof;

FIG. 11 is a rear view thereof;

FIG. 12 is a left side view thereof;

FIG. 13 is a top view thereof; and,

FIG. 14 is a bottom view thereof.

The dashed lines of the heart shaped pedal represent the bounds of the claimed design and form no part of the claimed design. Additionally, the unshown portion of the heart shaped pedal forms no part of the claimed design.
